UNITED STATES PATENT OFFICE.

WHEELER H. VIBBER, OF NEW LONDON, CONNECTICUT, ASSIGNOR OF ONE-HALF TO THE GILLETTE-VIBBER CO., OF NEW LONDON, CONNECTICUT, A CORPORATION OF CONNECTICUT.

ELECTRIC GROUNDING CONNECTION.

Application filed February 6, 1925. Serial No. 7,373.

This invention relates to ground connections of electric wiring systems and metallic electrical conduits to grounded pipes, such as the ordinary water piping system of a building, or a pipe or rod specially driven for the purpose. The principal object of the invention is to provide means for insuring a permanent and reliable grounding contact connection of the grounding wire and metallic conduit with the grounded pipe, the means to attain this end also including provision for clamping and connecting the grounding conduit which encases the grounding wire securely in pre-determined relation to the grounded pipe. The foregoing and other objects and advantages of the invention will more fully appear from the following detailed description taken in connection with the accompanying drawings, and the distinctive features of novelty will be pointed out in the appended claims.

Referring to the drawings;

Fig. 1 is an elevation with a portion in section showing one embodiment of the invention and showing a portion of a grounded pipe and of a grounding conduit.

Fig. 2 is a transverse section on line 2—2 of Fig. 1.

Fig. 3 is a side elevation showing another embodiment of the invention.

Fig. 4 is a transverse section on line 4—4 of Fig. 3.

Fig. 5 is an elevation showing still another embodiment of the invention.

Fig. 6 is a transverse section thereof on line 6—6 of Fig. 5.

Fig. 7 is an elevation showing still another form of the invention; and

Fig. 8 is a transverse section thereof on line 8 of Fig. 7.

Referring first to Figs. 1 and 2, 10 indicates a grounded conductor such as an ordinary water pipe. This conductor pipe has secured thereto at a selected point a clasp band 11 of suitable conductive metal such as copper. This clasp band has ears 12, 13 projecting at one side thereof, the ear 13 being shown as having a turned-in extremity 13^a extending in parallelism with, and adjacent the ear 12. Through apertures of these ears a screw 14 is passed, this screw being selected in size according to the size of the pipe, the clasp being adjustable in this way so as to fit different sizes of pipe.

55 This screw is threaded through a strap ex-

tremity 15^a of a bracket 15, which thus serves as a nut whereby on turning up the screw 14 the clasp-band 11 is securely clamped to the pipe 10. The use of the screw 14 as the means for securing together the socket holder 60 or bracket 15 and the clasp-band 11 enables the bracket 15 to be pivotally adjusted about the screw 14 so that the grounding conduit may be disposed at various angles with respect to the pipe 10. The clasp-band 11 is 65 provided with spaced apart apertures 16 through which an exposed end portion 17^a of a conductor wire is adapted to be passed so as to lie within the clasp 11 in position to be clamped strongly and securely against the 70 pipe 10 as the clasp is thus tightened thereupon. This grounding wire is encased by a grounding conduit pipe 18 which may be of usual type. In accordance with my invention a threaded extremity 18^a of this grounding conduit is engaged in a threaded socket 75 15^b which forms a part of the bracket 15 and is hence clamped immovably to the pipe 10, by means of the strap portion 15^a, by the same adjustment of the screw 14 which secures the clasp 11 to the pipe.

In Figs. 3 and 4 I show a form of the invention employing a clasp-band 111 which is provided with ears 112, 113 through which is passed a clamp screw 114 which draws up 85 the clasp-band onto the pipe 10 with an exposed section of the conductor wire 117^a interposed underneath an angular extent of said clasp-band as already described. In this case the bracket member 115 is fashioned 90 from a continuous strap of metal which has one extremity bent and tapped to form a nut portion 115^a which engages the screw 114, thence said strap extends outward and is bent to form a circular holder or socket 115^b in 95 which the protective conductor 18 is engaged and preferably screwed, thence the extremity of the strap extends inward to form an ear 119 in which a clamp screw 120 is threaded to prevent the socket from opening and to 100 hold it clasped upon the pipe 18.

In Figs. 5 and 6 I show a form of the invention where the grounding pipe 10 has fitted thereon two spaced apart clasp-bands 211, 211'. These clasps have ears 212, 213 105 through which is passed a clamp screw 214 the same as already described. The clamp screws on each of the clasp-bands engage oppositely extending extremities 215^a of a strap hanger 215 which has an intermediate portion 110

thereof bent to form a circular socket 215^b which may be internally threaded to receive the threaded extremity of the grounding conduit 18. The clasp-bands 211, 211' are provided with spaced apart apertures 216 permitting an exposed end portion 217^a of the conductor wire to be passed through the apertures of one clasp and then of the other to be pressed against the pipe 10 as already described.

In Figs. 7 and 8 there are also two clasp-bands 311, 311' provided with ears 312, 313 through which is passed a clamp screw 314 as already described. In this form the screws 314 are threaded into one side 315^a of an angular plate 315, the other side 315^b of which has a threaded opening into which the end of the conduit pipe 18 is threaded. The clasps in this case have spaced apart apertures 316 to receive an exposed portion 317^a of the conductive wire 317 which in this form, and as in the form of Figs. 5 and 6, may be looped around so as to be engaged underneath both of the clasp bands. The angular plate 315 may be provided with threaded apertures 318, at the opposite side thereof from those with which the screws 314 are shown as engaged, so that the clasp bands for attachment to the water pipe may be applied to either side or end of the angular plate as may be most convenient.

The described fitting is adapted for use not only in connecting a grounding conduit with a grounded water pipe or the like, but it can also be used for connecting a grounding conduit to a pipe or rod specially driven to serve as a grounded element. The fitting is also adapted to be used without the use of any ground wire. When so used it is employed for grounding the metallic conduit that would contain the circuit wires. It may also be employed when it may be desired to connect two conduits together, and also in cases where it might be necessary or desirable to connect two conduits together with the grounding conduit connected between the two fittings at an angle. The fitting shown in Figs. 1 and 2 is adapted for this purpose, it being noted that the socket 15^b has its inner extremity rounded so as to provide clearance for angular adjustment with reference to the clasp. The form shown in Figs. 3 and 4 is likewise adapted for such angular adjustment, and likewise the forms of Figs. 5 and 6, 7 and 8, it being only necessary in these latter forms to bend or twist the strap hanger members to a greater or less extent, which is easily possible since these are made of a steel adapted to stand such bending.

I am aware that the invention may be embodied in other specific forms without departing from the spirit or essential attributes thereof, and I therefore desire the present embodiment to be considered in all respects as illustrative and not restrictive, reference be-

ing had to the appended claims rather than to the foregoing description to indicate the scope of the invention.

Having described my invention, what I claim as new and desire to secure by Letters Patent is:

1. An electric ground connection comprising a conducting pipe, a clasp-band looped around the pipe and having out-turned and apertured ends opposed to each other, a grounding conduit bearing a conductor wire having an exposed end inserted between the clasp-band and the pipe, a socket holder in which one end of the conduit is secured, and a binding screw extending through the apertured ends of the clasp-band and having threaded engagement with a portion of the socket holder to clamp the band and the conductor wire to the conductor pipe and to secure the socket holder to the band, the binding screw and the parts engaged thereby being constructed and arranged to permit angular adjustment of the socket holder relatively to clasp-band.

2. An electric ground connection comprising a grounded conductor pipe, a clasp-band wrapped around the pipe, said band having out-turned ends arranged opposite each other and an aperture located between said ends, a grounding conduit, a socket holder in which one end of the conduit is secured, a conductor wire carried by the grounding conduit and having an exposed end extending from said conduit to the outside of the clasp-band and thence through said aperture to a position between the clasp-band and the pipe, and tightening means passed through the out-turned ends of the clasp-band and engaged in a portion of the socket holder detachably to secure the socket holder to the clasp-band and rigidly to clamp the clasp-band and the conductor wire to the conductor pipe.

3. An electric ground connection comprising a conducting pipe, a clasp-band looped around the pipe and having out-turned and apertured ends opposed to each other, a grounding conduit carrying a conductor wire having an exposed end extending from the end of the conduit, a socket holder in which said conduit end is secured, a binding screw extending through the apertured ends of the clasp-band and having threaded engagement with a portion of the socket holder to clamp the band to the conductor pipe and to secure the socket holder to the band, the binding screw and the parts engaged thereby being constructed and arranged to permit angular adjustment of the socket holder relatively to the clasp-band, and means for securing the said exposed end of the conductor wire to said clasp-band.

4. An electric ground connection comprising a clasp-band adapted to be looped around a conducting pipe and having out-turned ends opposed to each other, a grounding con-

duit carrying a conductor wire having an exposed end, a socket holder for securing the end of the conduit, unitary means for clamping the band to the conductor pipe and for securing the socket holder to the said out-turned ends of the band, said means being constructed and arranged to permit an- gular adjustment of the socket holder relatively to the clasp-band, and means for securing the said exposed end of the conductor 10 wire to said clasp-band.

In testimony whereof I affix my signature.

WHEELER H. VIBBER.
